APPARATUS FOR THE TREATMENT OF PAPER
Sydney James Green and David Sydney Goodfellow,
Southampton, England, assignors, by mesne assignments,
to Brown and Williamson Tobacco Corporation,
Louisville, Ky., a corporation of Delaware
Filed Aug. 10, 1961, Ser. No. 130,658
9 Claims. (Cl. 51-8)

This invention relates to apparatus for treating paper, to roughen, thin or perforate it. One application of the invention is for treating cigarette paper so as to increase the rate at which air can be drawn through it.

According to the invention, the paper is subjected to a stream of particles of an abrasive substance. The stream of particles may be carried by a blast of air, or it may be projected from a rotating distributor. If desired, the blast may be directed on to limited areas of the paper by means of a mask. The apparatus of this invention may be employed to roughen the surface of the paper, to perforate it or to effect a reduction in its thickness. In the case of cigarette paper, such perforation or reduction of thickness allows air to be drawn through the treated portion of paper when a cigarette having a wrapper made thereof is being smoked, thereby diluting and cooling the smoke, and also provides means for marking patterns, symbols, letters or trademarks on cigarettes. The apparatus of this invention may also be used for applying patterns of perforations or of thinned portions to other paper articles, such as postage stamps and banknotes, for example.

When the apparatus is used to perforate cigarette paper, the perforations may be produced along the whole length of a cigarette paper web before it is used for forming the wrappers of cigarettes, or the perforations may be produced over bands of specified width arranged to occur at any desired position on the cigarettes. The holes produced by this apparatus may be round or of any other shape and of any desired size. Similarly, the holes or perforations may be arranged in a pattern to form letters or numerals or a symbol or picture or trademark.

When the apparatus is used to roughen or to effect a reduction in the thickness of cigarette paper, the roughening or thinning of the cigarette paper web may be effected along its whole length or over bands of specified width arranged to occur at any desired position in the cigarette. The portion of roughened or thinned paper may be arranged in a pattern to form letters or numerals, a symbol, picture or trademark. Taking a specific case, parallel bands could be made longitudinally along the cigarette paper, or across the cigarette to give a ringed effect.

The apparatus according to the invention comprises means for projecting a stream of particles of an abrasive material and means for moving a paper web across the path of the stream of abrasive particles.

Particular embodiments of the invention will now be described by way of example and with reference to the accompanying drawings, in which:

FIGURE 1 is a diagrammatic elevation of an apparatus for treating cigarette paper,

FIGURE 2 an elevation, partly in section, of an alternative apparatus for this purpose,

FIGURE 3 an enlarged cross-section of part of the apparatus of FIGURE 2,

FIGURE 4 a diagrammatic cross-sectional view of a third form of apparatus for the same purpose,

FIGURE 5 a perspective view of a rotary distributor for abrasive, and

FIGURE 6 shows specimens of various patterns which

2

may be produced on cigarette paper by the apparatus shown in the preceding figures.

In the apparatus shown in FIGURE 1, a web 1 of cigarette paper is led through a passageway provided in the top of a vessel 2 containing particles of an abrasive substance. The vessel 2 has a central mixing tube 3 with a nozzle 4 at its upper end, and an air supply tube 5 is disposed axially within the mixing tube 3. Abrasive can enter the mixing tube 3 through an aperture 6, under the suction effect produced by air flow through the air supply tube 5. A mask in the form of a thin flexible metal band 7, preferably of steel, runs between the paper web 1 and the nozzle 4 and over pulleys 8, 9, 10, 11. The pulley 8 is driven through a belt 12.

Along the metal band 7, at intervals of one cigarette length, is punched or etched the pattern it is desired to reproduce on the cigarette paper, whether it be a perforated pattern or a pattern to reduce the thickness of the cigarette paper or roughen it over a prescribed area. The metal band 7 travels at the same speed as the cigarette paper web 1, which passes straight to the cigarette making machine, in fact both the band 7 and web 1 may be driven by the cigarette making machine. Air supplied through the tube 5 entrains particles of abrasive and ejects them through the nozzle 4 against the band 7 and paper web 1. At the point or area of treatment, the side of the paper web 1 opposite to the band 7 runs against a plate 13 of hardened steel or other hard material. The jet of abrasive material plays continuously on the metal band 7 which forms a mask or stencil allowing the jet of abrasive to perforate, roughen or thin by abrasion only the area required. The system is continuous as the abrasive after striking the band 7 drops down into the vessel 2 to be used again as required.

FIGURES 2 and 3 show an alternative form of apparatus. In this embodiment, the cigarette paper web 1 is led from a bobbin 14 into a chamber 15, round a roller 16 and out of the chamber 15 to the cigarette making machine (not shown). Where the paper web 1 enters and leaves the chamber 15, seals 17, 18 are provided. The roller 16 is of rubber with steel side plates 19 and a thin flexible steel rim 20 which acts as a backing plate (FIGURE 3). The abrasive is stored in a funnel 21 below the roller 16 and is sucked up through a pipe 22 to a mixing chamber 23 by a current of air supplied through a pipe 24 and passing through the mixing chamber 23 to a nozzle 25. The abrasive is ejected by the blast of air from the nozzle 25 against the inside of the rim 26 of a wheel 27. The rim 26 carries inserts, such as that shown at 28, in the form of masks or stencils, spaced at intervals, to allow the abrasive to act on the paper web 1 at the required positions. The wheel 27 is preferably driven from the cigarette making machine. The operation is continuous, as the abrasive after ejection from the nozzle 25 falls back into the funnel 21. A dust extractor may be provided as shown schematically at 29. More than one nozzle 25 may be used. The rubber core of the roller 16 may be made in tube form and inflated. Means (not shown) may be provided for cleaning the paper after treatment.

FIGURE 4 shows a further alternative form of apparatus. The bobbin 14, roller 16 and wheel 27 with inserts 28, in the form of masks or stencils, in its rim 26, are all as shown in FIGURES 2 and 3, and the roller 16 and wheel 27 are enclosed within a chamber 30, the paper web 1 passing in and out of the chamber 30 through seals (not shown) similar to those shown at 18 and 19 in FIGURE 2. In this apparatus, the chamber has two conical partitions 31, 32, one below the other, each with a normally open diaphragm or conical valve 33, 34 at its lowest point. The bottom 35 of the chamber 30

is also conical and at its lowest point communicates through a valve 36 with a mixing chamber 37 in a compressed air supply pipe 38. The partitions 31, 32 in effect define two compartments 39, 40 below the main part of the chamber 30.

The compressed air supply can be connected to either of the compartments 39, 40 and to the mixing chamber 37 by means of valves 41, 42, 43. From the mixing chamber 37, a pipe 44 leads the mixture of air and abrasive to a nozzle 45 disposed similarly to the nozzle 25 of FIGURES 2 and 3. A moisture trap 38a may be provided in the compressed air supply line.

In operation, the valves 36, 41, 42, 43 are first closed and abrasive is placed in chamber 30. As the valves 33, 34 are open, this abrasive falls down into compartment 40. Valve 42 is then opened, so that compartment 40 is pressurized and valve 34 is thereby closed. On opening valves 36 and 43, abrasive under pressure is mixed with the compressed air in the mixing chamber 37, is forced through pipe 44 to nozzle 45 and ejected therefrom against the inside of rim 26 and, through inserts 28, against the paper web 1. This abrasive then falls down through the open valve 33 into compartment 39. When the level of abrasive in compartment 40 becomes low, valve 41 is opened and valve 42 closed for a short period. The pressure in compartment 39 causes valve 33 to close and valve 34 to open, allowing the abrasive which has collected in compartment 39 to fall into compartment 40, without interrupting the operation. Valve 42 is again opened and valve 41 closed, and operation continues.

This apparatus has the advantage that the abrasive is under pressure before being introduced into the air stream, which has the effect of increasing the velocity of the abrasive particles, resulting in a higher efficiency jet.

The valves 36 and 43 may be controlled from the cigarette making machine to which the paper web 1 is led.

The valves 41 and 42 may be controlled automatically by cams or by a timer motor.

Instead of using a blast of air to carry the stream of abrasive particles, use may be made of a rotating distributor employing centrifugal force and/or vanes to project the abrasive stream. FIGURE 5 shows such a rotating distributor, in which abrasive is supplied through a pipe 46 to a hollow hub 47 disposed between and secured to discs 48, 49. On rotation of the discs and hub, abrasive is ejected through apertures 50 in the hub by centrifugal force. Vanes 51 disposed between the discs 48, 49 give an added velocity to the abrasive particles by a "batting" action.

The particular abrasive material used may be any one of a large variety of materials, such as sand, ground glass, zircon, garnet, steel, Corborundum, or even fruit stones, all in the form of finely divided particles. The choice of abrasive material is governed by the degree of perforation, thinning or roughening which it is desired to effect on the paper.

The mask or stencil, such as the inserts 28, may be made of other materials besides metal—plastic or ceramic, for example.

In FIGURE 6 are shown seven examples of different types of pattern, letters, symbols and trademarks which can be applied to cigarette paper by means of the apparatus described above.

Although the specific forms of apparatus described above are intended for treating cigarette paper, the invention can also be employed for treating other types of paper product, e.g., for perforating postage stamps or for applying a pattern or marking to bank notes.

We claim:

1. Apparatus for treating paper to roughen, thin or perforate it, comprising a mask in the form of a rotatable cylindrical surface provided with apertures, means for

5 projecting a stream of particles of an abrasive material against the inside of the said rotatable cylindrical mask, a rotatable backing roller having a flexible metal surface which co-acts with the outside of the said rotatable cylindrical mask at the point where the abrasive stream strikes the said mask, and means for leading a web of paper between the said mask and the said backing roller at the said point of co-action.

2. Apparatus according to claim 1, wherein the said rotatable cylindrical mask is formed by an axially projecting rim on the circumference of a wheel, the said apertures being provided in inserts in the said rim.

3. Apparatus according to claim 2, wherein the means for projecting a stream of abrasive particles comprises a nozzle disposed within the circumference of said axially projecting rim.

20 4. Apparatus according to claim 1, wherein the means for projecting a stream of abrasive particles comprises a rotary distributor.

5. Apparatus according to claim 1, wherein the backing

25 roller has a core which is of tube form and inflatable.

6. Apparatus for treating paper to roughen, thin or perforate it, comprising a rotatable cylindrical mask provided with apertures, a nozzle, an air supply pipe connected to the said nozzle and adapted to project a stream 30 of abrasive particles in a blast of air through said nozzle against the inside of the said mask, a rotatable backing roller having a flexible metal rim and a resilient core, which backing roller co-acts with the outside of the said cylindrical mask at the point where the abrasive stream 35 strikes the said mask, means for leading a web of paper around said backing roller and between said mask and said backing roller at their point of co-action, and means for rotating the said mask to draw said web through the apparatus and to expose limited areas of said web to the action of said abrasive stream.

30 7. Apparatus according to claim 6, comprising also a receptacle disposed so as to receive the abrasive particles after they have struck the mask or the paper web, and means for supplying the abrasive particles from the receptacle to the nozzle.

8. Apparatus according to claim 7, wherein the means for supplying the abrasive particles from the receptacle comprises a further pipe joining the receptacle to the air supply pipe in such manner that passage of air through 50 the air supply pipe to the nozzle creates a suction effect in the said further pipe.

9. Apparatus according to claim 7, wherein the means for supplying the abrasive particles from the receptacle comprises a series of compartments adapted to receive 55 the abrasive particles and adapted to be placed under pressure, the last of said compartments being connected to the air supply pipe so that the abrasive particles can be supplied to the said supply pipe under pressure.
